(57) **CLAIM**

The ornamental design for a foldable cart, as shown and described.

DESCRIPTION

FIG. 1 is a perspective view of a foldable cart in a top open configuration, according to the present application; FIG. 2 is a perspective view of a foldable cart in a top closed configuration;

FIG. 3 is a front plan view thereof;

FIG. 4 is a rear plan view thereof;

FIG. 5 is a right plan view thereof;

FIG. 6 is a left plan view thereof;

FIG. 7 is a top plan view thereof;

FIG. 8 is a perspective view of a foldable cart in a front open configuration;

FIG. 9 is a front plan view thereof;

FIG. 10 is a perspective view of a foldable cart in a front open and shelf folded configuration;

FIG. 11 is a front plan view thereof; and,

FIG. 12 is a top plan view of a foldable cart in a folded configuration.

The broken lines in the drawings depict portions of the foldable cart that form no part of the claimed design.

1 Claim, 10 Drawing Sheets
